ATTORNEY

UNITED STATES PATENT OFFICE.

LEONARD ROLL, OF WILKES-BARRÉ, PENNSYLVANIA.

GRATE-BAR.

SPECIFICATION forming part of Letters Patent No. 335,540, dated February 2, 1886.

Application filed November 19, 1885. Serial No. 183,365. (No model.)

To all whom it may concern:

Be it known that I, LEONARD ROLL, a citizen of the United States, residing at Wilkes-Barré, in the county of Luzerne and State of Pennsylvania, have invented a new and useful Improvement in Grate-Bars, of which the following is a specification.

The objects of my invention are, first, to provide a grate-bar with expansion top plates 10 with lateral supports to prevent them from warping upward; second, to provide a grate-bar with a rib or bearing-bar which shall be stronger than the ordinary form without a corresponding increase of material. I attain 15 these objects in the grate-bar illustrated in the accompanying drawings, in which—

Figure 1 is a plan view. Fig. 2 is a side elevation. Fig. 3 is a cross-section showing a joint hereinafter referred to. Fig. 4 is a 20 cross-section on line 1 and 2. Fig. 5 is a cross-section on line 3 and 4, and Fig. 6 is an end view.

Similar letters refer to similar parts throughout the several views.

25 My invention relates to a grate-bar of which the top plate may be of any of the usual forms; but the supporting-rib or bearing-bar is of the form of an annular elongated ellipse hung on its major axis, and may be entirely 30 separate from the top plate. To the ends of the rib are cast solid with it the bearing-heads *g* and *h*, on which the bar is hung and on which is formed a dovetail which engages with a suitable recess in the top plate, *a*, formed by 35 the lug *c* and *e*; also in the upper side of the heads *g* and *h* are formed the recesses *k*, that the air may have all possible access to the top plate. Similar recesses, *j* and *l*, are formed in all supporting-brackets hereinafter referred to.

40 On the side of the rib *b* are cast the brackets *f*, connecting the upper and lower chords of the rib. The upper or projecting ends have formed on them similar dovetails, as on *g* and *h*, and 45 engage with the lugs *d* on the side of the top plate, *a*. This construction will prevent the top plate from warping or bending upward under heat, and leave it free to expand in either direction at will. The method of separating the top plate from the rib with an interlocking loose joint is further illustrated in

Fig. 3. This is a modified form of said joint and may be used throughout the bar, instead of that shown in the other figures. At the center of the length of the rib the top plate 55 may be cast solid with it through the bracket *e*.

I do not presume that this method of providing for expansion in the top plate of a grate-bar independent to that of the rib is new, but that the addition of the brackets *f* 60 and lugs *d* are new and a necessity, in order to prevent warping of the top plate, especially in long bars, since these have a tendency without such support to bend upward, notwithstanding their free longitudinal expansion. 65 These brackets may be located at one or more points between the center and the ends of the bar, as circumstances require. I also think that the form and construction of the rib *b* is new in a grate-bar, and it is seen from 70 the illustration that its form is the strongest for an equal amount of material, since the resistances to lateral stress are the extreme tensile and compression from the neutral axis, and with the brackets *f* acting as struts give 75 it a strength far beyond that obtainable in the usual form of rib from a greater amount of material.

Having described my invention, and being aware that grate-bars have been made in which 80 expansion has been provided for, as above described, I do not claim such wholly; but

What I do claim, and desire to secure by Letters Patent, is—

1. In the within-described grate-bar, the rib 85 *b*, having the form of an annular elongated ellipse to which are cast solid the bearing-heads *g* and *h*, as described.

2. In the within-described grate-bar, the brackets *f* and *e* to form struts in the rib *b*, 90 and supports for the top plate, *a*, in combination with the rib *b* and bearing-heads *g* and *h*, as described.

3. In the within-described grate-bar, the combination, with a top plate, *a*, of a rib, *b*, 95 bearing-heads *g* and *h*, and brackets *f* and lugs *d*, substantially as described.

LEONARD ROLL.
